UNITED STATES PATENT OFFICE.

CALVIN KELLER, OF CREIGHTON, NEBRASKA.

INKSTAND.

SPECIFICATION forming part of Letters Patent No. 758,257, dated April 26, 1904.

Application filed February 15, 1898. Serial No. 670,412. (No model.)

To all whom it may concern:

Be it known that I, CALVIN KELLER, residing at Creighton, in the county of Knox and State of Nebraska, have invented certain useful Improvements in Inkstands; and I do hereby declare that the following is a full, clear, and exact description of the invention, such as will enable others skilled in the art to which it appertains to make and use the same, reference being had to the accompanying drawings, which form a part of this specification.

This invention relates to a novel improvement in inkstands.

The object of my invention is to provide a neat, simple, and useful inkstand which shall embody a self-closing cap, as will be described more fully hereinafter.

In the accompanying drawings I have shown in Figure 1 a front elevation of an inkstand embodying my invention, while Fig. 2 shows a top view in section on lines *xx* of Fig. 1. Fig. 3 is a side elevation with the outer wall broken away.

My invention comprises, essentially, a three-sided housing comprising the back A, the two ends 1, 1, and the bottom 2. Approximately centrally the housing is provided with a transverse partition 3, which extends upward a suitable distance and is provided with the front 4 upon one side. The partition 3 and front 4 form a closure, together with one of the sides 1, the bottom 2, and a portion of the back A, as is shown in Fig. 2. This closure is again provided with a transverse

partition 6, extending upward a suitable distance and being provided with the top 7, so that a second closure formed of a part of the back A, a part of the side 1, a portion of the bottom 2, the side 6, and the top 7 is provided adapted to hold an ordinary drawer 8, as is shown. This drawer is intended to contain stamps or any other suitable desk-supplies, as is also the main closure formed by the front 4 and side 3, which is provided with a removable top 5.

The ink stand or well used in connection with my device may be of any suitable size or material, as long as it is provided with a smooth top.

At a suitable point and extending horizontally above the ink-well B is a shaft D, of

wire or any other suitable material, which shaft is provided with the cranks 10 and 12, the crank 10 passing through a weighted head *c*, which is adapted to be snugly held upon the top of the well, so as to close the same, the upper portion of this weighted top being provided with a pincushion or pen-wiper C, as is disclosed. These cranks 10 and 12 extend in one plane. Depending from the crank 12 is a bar *a*, which is at its lower end secured to the eye 13 of the stem 15, forming part of the operating-bar K, which operating-bar works within an opening of one of the walls 1, passing through the transverse wall 3 and then backward a little beyond the shaft D, to be engaged by the bar *a*, as is shown in Fig. 3. The lever portion K is placed in front and is inclined upward a suitable distance, so that it can be easily depressed.

The operation of the device would be as follows: The operator in dipping his pen would place his fingers upon the lower lever K, which movement would carry upward the stem 15, and this stem 15 would carry up the connected bar *a*, which in turn would carry upward the crank 12 to actuate the shaft D, so that the weighted cap would be carried upward, disclosing the opening of the ink-well. The pen would then be dipped in the well, and as soon as the fingers were withdrawn from the lever K the weighted cap *c* would automatically close the ink-well.

The device is exceedingly simple of construction.

Having thus described my said invention, what I claim as new, and desire to secure by United States Letters Patent, is—

An ink-well comprising a housing formed by the combination with a base, of a back, and two sides, of a transverse partition secured to said back and base, an open-topped ink-well positioned upon one side within said housing, a shaft extending lengthwise across said housing above the top of said ink-well, said shaft being provided with one crank immediately above the top of the ink-well and a second crank extending in a like plane adjacent said first crank, an ink-well top secured to said first-mentioned crank, a bar depending from said last-mentioned crank, and a lever, as K, pivotally held within the for-

ward end of said housing and provided with an extending stem secured to aforesaid bar arranged so that when said lever K is dipped downward the rearward end of said lever K is raised upward to carry upward said first-mentioned crank to raise the top of the ink-well, as and for the purpose set forth.

In testimony whereof I affix my signature in presence of two witnesses.

CALVIN KELLER.
